(57) **CLAIM**

The ornamental design for a beverage container as shown and described.

DESCRIPTION

FIG. 1 is a front view of a beverage container showing my new design;

FIG. 2 is a top view thereof;

FIG. 3 is a bottom view thereof;

FIG. 4 is a cross-sectional view thereof, taken in the direction of line 4-4 in FIG. 2;

FIG. 5 is a first perspective view thereof;

FIG. 6 is a second perspective view thereof; and,

FIG. 7 is an enlarged sectional view of the leg portion.

The broken lines shown are included for the purpose of illustrating portions of the beverage container that form no part of the claim.

1 Claim, 4 Drawing Sheets
